UNITED STATES PATENT OFFICE.

CHARLES A. DUNN, OF WEST HOMESTEAD, PENNSYLVANIA.

ENVELOP.

SPECIFICATION forming part of Letters Patent No. 707,308, dated August 19, 1902.

Application filed March 21, 1902. Serial No. 99,265. (No model.)

To all whom it may concern:

Be it known that I, CHARLES A. DUNN, a citizen of the United States of America, residing at West Homestead, in the county of Allegheny and State of Pennsylvania, have invented certain new and useful Improvements in Envelops, of which the following is a specification, reference being had therein to the accompanying drawings.

10 This invention relates to certain new and useful improvements in envelops, and relates more particularly to that class that cannot be opened without detection.

15 The invention has for its object the provision of novel means whereby any tampering with the envelop may be easily discerned; furthermore, to construct the locking edges in a manner that will securely seal the envelop and retain the contents in proper position therein.

20 The invention further aims to provide an envelop of the above-described character that will be extremely simple in construction, strong, durable, comparatively inexpensive 25 to manufacture, and highly efficient in its use.

With the above and other objects in view the invention consists in the novel construction, combination, and arrangement of parts to be hereinafter more fully described, and 30 specifically pointed out in the claims.

In describing the invention in detail reference is had to the accompanying drawings, forming a part of this specification, and wherein like numerals of reference indicate like 35 parts throughout the several views, in which—

Figure 1 is a plan view of my improved envelop-blank. Fig. 2 is a similar view showing the securing-flap placed in position and the upper tongue applied to the securing-flap.

40 Fig. 3 is a plan view of the envelop when sealed. Fig. 4 is an enlarged detail view of the elongated strip for securing the end and sides of the envelop.

In the drawings, 1 represents the front, and 45 2 the back, of the envelop, said back 2 having a cut-away portion 3 in its free edge, and the front 1 is provided with two vertical slits extending but a short distance into the body of the front, thus forming a tongue 4 of substantially the same length as the cut-away portion 3 in the back 2. This tongue is gummed, 50 and when the back and front are brought to-

gether or folded the tongue 4 is adapted to be folded over and engage the back, as shown in Fig. 2. This fold is of course not made 55 until after the letter has been placed in the envelop. The front 1 is of slightly greater length than the back 2 and is provided with crease-lines, so that the extended portions 5 may be bent over and form securing-flaps, 60 they being gummed to adhere to the back 2. The blank is formed with securing-strips of unequal length at its ends. These strips are made integral with the blank centrally of its ends, the strip 6 at one end having an ex- 65 tension 7, which is adapted to be folded upon the edges of the front and back after the latter have been folded and the letter placed in the envelop. The strip 9 at the opposite end of the blank is adapted to fold against the 70 end of the envelop. These strips 6 and 9 and the extension 7 of the strip 6 are provided with a crease 10, extending throughout the length of the strips and also forming the crease-line or fold-line between the front and 75 back. When, therefore, the securing-strips are folded and doubled on their crease-line, 80 they embrace both the back and front at the ends of the envelop, while the extension 7 embraces the upper edge of the envelop. 85 The strips and extension are gummed to adhere to the back and front when folded into position. In order to permit the easy folding of the strips 6 and 9 into upright position and the folding over of the extension 7 onto 90 the edge of the envelop, I provide the strips 6 and 9 and also the extension 7 with V-shaped crease-lines 8, as shown in Fig. 1. To form the envelop from the blank, the front 1 and back 2 are folded on the central crease-line 10 of the blank and the gummed flaps 5 then folded over so as to adhere to the back 2. With the folding of the back and front 95 the securing-strips may be doubled on their central crease-line, and the envelop is now in condition to receive the contents. After the latter has been placed in the envelop the tongue 4 is folded over and engaged with the back, the strips 6 and 9 folded against the ends and adhered to both front and back, 100 and the extension 7 folded on the edge of the envelop and adhered to front and back, when the seal is completed. Although, as herein described, 1 is designated as the front, and 2

the back, yet it will be observed that both sides of the envelop are the same when the seal is completed, so that either side thereof may be used as the front or address side.

5 It will be noted that various changes may be made in the details of construction without departing from the general spirit of my invention.

Having fully described my invention, what 10 I claim as new, and desire to secure by Letters Patent, is—

1. An envelop-blank consisting of a front and back, the front being of greater length than the back to form wings adapted to fold 15 on said back, and securing-strips formed integral with the front and back and adapted to be doubled so as to engage both the front and back, substantially as described.

2. An envelop comprising a blank having 20 a front forming one side of the envelop and a back forming the other side of said envelop, the front being of greater length than the back and adapted to have its extensions folded over to engage the back, a tongue carried by 25 the front adapted to engage with the back,

and end-securing strips carried by the blank, one of said strips adapted to engage the one end of the envelop, and the other strip adapted to engage the opposite end and the edge of the envelop, substantially as described. 30

3. In an envelop, the combination of an upper and a lower securing-flap, one of said flaps carrying a securing-tongue and the other of said flaps having a cut-away portion adapted to receive said securing-tongue, securing ends carried by said flaps intermediate their ends, said securing ends adapted to be creased and bent upwardly to inclose the sides of the upper and lower securing-flap, one of said securing ends adapted to be bent 40 over the upper sides of the said upper and lower securing-flaps and adapted to inclose said securing-tongue, substantially as described. 35

In testimony whereof I affix my signature 45 in the presence of two witnesses.

CHARLES A. DUNN.
